UNITED STATES PATENT OFFICE

CHARLES J. VAN DEPOELE, OF CHICAGO, ILLINOIS.

ELECTRO-MAGNETIC RECIPROCATING ENGINE.

SPECIFICATION forming part of Letters Patent No. 317,249, dated May 5, 1885.

Application filed April 5, 1884. (No model.)

To all whom it may concern:

Be it known that I, CHARLES J. VAN DEPOELE, a citizen of the United States of America, residing at Chicago, in the county of Cook and State of Illinois, have invented certain new and useful Improvements in Electro-Magnetic Reciprocating Engines, of which the following is a specification, reference being had therein to the accompanying drawings.

10 My invention relates more particularly to certain improvements in that class of electric motors wherein a core has an endwise motion in a solenoid; and the invention consists in certain combinations and peculiarities of construction and arrangement of parts, which will be more fully described, and then pointed out in the claims.

15 In the accompanying drawings, Figure 1 represents a plan view of an engine with the solenoids in section; Fig. 2, a side view of the same; Fig. 3, a detail showing a side view of the central rod and its attachments and a central bar. Fig. 4 is an end view of the frame. Figs. 5 and 6 are side and end views, respectively, of the preferable arrangement of the solenoids. Fig. 7 is an end view of an arrangement of four solenoids with their cores. or other tool. As soon as the drill meets an obstruction—such, for instance, as the bottom of a drill-hole—the inertia of the loose tappet *d* causes it to overcome the strength of the light spring *r* and run along the rod *D* until it strikes the lower end of the contact-bar *E*, moving it into the position shown in Fig. 3, and thus breaks the connection. As soon as this is done the spring *r* draws back the tappet *d*, and as the electrical connection is broken by the movement of the contact-bar the solenoid loses its power, and the spring *R* draws back the rod *D* and drill *D'* until the tappet *d'* strikes the lower end of the contact-bar and pushes it in the position shown in Fig. 2, when the solenoids are again energized and the motion of the cores *C* and rod *D* repeated. It will be observed that as the contact-bar *E* moves sidewise it of necessity comes in contact with the different contacts *e e e* successively, by which means the current is admitted to the different sections *s*, one after the other, whereby all the destructive effects from the spark are avoided. The same thing of course occurs when the connection is broken, as the connection with each section *s* is broken separately.

I have thus far referred to the cores *C* as if they were of the ordinary constructions; but I prefer to make mine hollow, as shown in Fig. 7, which may be readily done by using gas or steam pipe properly turned to the right size. It is advisable to split such tubes down one side, as shown in Fig. 7, which will make the magnetization much more rapid whether single or multiple solenoid rods are used.

The reason I prefer a large number of solenoids and cores is that I have found that when large bodies of iron are subject to magnetization and demagnetization it takes considerable time to bring the magnetization up to its maximum, and that consequently engines where this principle is employed in which the cores are large and heavy work very sluggish and waste a good deal of electrical energy, whereas in the case of multiple cores and corresponding solenoids a very rapid magnetization will be the result, so that the apparatus constructed on this principle will be capable of a very rapid reciprocating motion and an economy of current will be the result since the action of the current need not be prolonged as in the case of heavy cores and large solenoids.

In the diagrammatic views, Figs. 8 and 9, I show two methods of working my engines, the first-named being to place the same in multiple arc and the other (shown in Fig. 9) having them arranged in series.

In the multiple-arc system, in order to avoid the spark, I divide the current up, as heretofore explained, by bringing the contact-bar *E* successively in contact with the outer terminals of the sections *s*, while the inner ends are connected to a conductor running along the solenoid, as before explained. This I consider the preferable plan.

At *c* in Fig. 8 is shown a double solenoid wound with single helices, but provided with a resistance which is gradually cut in or out of circuit, so as to avoid the spark at the moment of breaking contact with the source of electricity.

Fig. 9 shows three engines arranged in series and how the current is made to act when the apparatus is so placed. Across the two terminals of the solenoids or helices is arranged a variable resistance, which can be gradually closed around said helices, so that when the bar *E* is upon the contacts *e e e* little current will pass through the helices, as it will find a shorter path through the variable resistance, which may be a similar device to that patented by me January 9, 1883. By moving the bar *E* from the contacts the resistance gradually increases, and thus shunts the main current through the helices until all the resistances are out of circuit, when all the current will pass through the solenoid.

Where the number of the solenoids in the cluster is comparatively large, I lessen the number of sections in each solenoid, and I sometimes use but a single coil to each solenoid when very large, as in Fig. 6, in which case I so arrange the terminals and contact-bar that the solenoids receive the current one after the other. Where only a weak power is required, and the solenoids and cores are very small, I pursue the same plan with a two-solenoid engine, and admit the current to one solenoid first and the other afterward.

What I claim as new is—

1. In an electric engine, a series of coils, a circuit-controller, electrical connection, and mechanism, substantially as described, operated by some moving part of the engine, whereby the power of said coils is gradually increased near the commencement of each stroke of the engine, as set forth.

2. In an electric engine, a solenoid, a core for the same, and a circuit-controller, electrical connections, and mechanism, substantially as described, operated by some moving part of the engine, whereby the power of the solenoid is gradually increased or diminished near the commencement and termination of each stroke of the engine, as set forth.

3. In an electric engine, the combination of a reciprocating core, a solenoid wound in sections, a circuit-controller, electrical connections, and mechanism, substantially as described, operated by some moving part of the engine, whereby the strength of said solenoid is gradually increased at the commencement of each stroke, as set forth.

4. In an electric engine, two or more cores moving simultaneously in combination with a like number of solenoids, each composed of two or more helices, and means, substantially as described, for gradually including said solenoids in a circuit near the commencement of each stroke, as set forth.

5. In an electric reciprocating engine, a cluster of cores, each provided with a solenoid

oid wound in sections, in combination with a circuit-breaker constructed to successively admit all of said sections into circuit near the commencement of the forward stroke of the engine, as set forth.

5 6. In an electro-magnetic engine having sectional solenoids, and as a means for successively bringing the sections of a solenoid into circuit, a contact-bar, as E, forming one terminal of all the sections of a single solenoid, in combination with a series of independent contacts, as e, each forming the other terminal of its respective section, substantially as described.

10 7. In a reciprocating electric engine, and in combination with the reciprocating core and circuit-breaker thereof, a tappet, d', moving with the core and actuating the contact-breaker to close the circuit and energize the solenoid, and a loosely-mounted tappet, d, normally held in position by a spring, but constructed and 15 arranged to move forward to operate the circuit-breaker on the cessation of the motion of the cores, substantially as described.

20 8. In an electric reciprocating engine, a contact maker or commutator actuated by a collar mounted upon a reciprocating part of the engine, and adjustably fixed thereto to deter-

mine the stroke of the parts in one direction, in combination with a loosely-mounted collar normally retained in place by a spring, and arranged to fly forward and actuate the commutator of the engine as soon as the forward thrust of the reciprocating parts is arrested or impeded, thereby causing a backward stroke to be made, substantially as described.

25 9. In a reciprocating electric engine, and in combination with the core and circuit-breaker thereof, a rod moving with said core, and a tappet, d', fixed on said rod to operate the contact-breaker in one direction, and a tappet, d, loosely mounted on the rod and 30 held normally in place by a spring, whereby on the stoppage of the rod the tappet will fly forward to operate the circuit-breaker and then return to its normal position, substantially as described.

35 In testimony whereof I have affixed my signature, in presence of two witnesses, this 1st day of April, 1884.

CHARLES J. VAN DEPOELE.
